UNITED STATES PATENT OFFICE.

RAYMOND H. VONDENBOSCH, OF HOLLYWOOD, CALIFORNIA.

HOT-BLAST FURNACE.

1,209,522.

Specification of Letters Patent. Patented Dec. 19, 1916.

Application filed December 14, 1915. Serial No. 66,687.

To all whom it may concern:

Be it known that I, RAYMOND H. VONDENBOSCH, a citizen of the United States, residing at Hollywood, in the county of Los Angeles and State of California, have invented new and useful Improvements in Hot-Blast Furnaces, of which the following is a specification.

This invention relates to hot blast furnaces, and pertains especially to furnaces which may be installed in the walls or floors of rooms.

It is an object of this invention to provide a self-contained furnace and register by which part of the air is heated indirectly by the burning fuel, and part is heated directly.

It is another object of this invention to provide a furnace which makes use of direct heating, but which will furnish warm air free from gas fumes, odor or smoke, and especially carbon monoxid.

I attain these objects by means of the embodiments of my invention illustrated in the accompanying drawing, in which:

Figure 1 is a perspective view of a floor furnace with parts broken away to better illustrate the path of the air and gases. Fig. 2 is a horizontal section taken on the line 2-2 of Fig. 1. Fig. 3 is an elevation of a wall furnace with part of the register plate broken away. Fig. 4 is a vertical section as seen on the line 4-4 of Fig. 3. Fig. 5 is a fragmentary horizontal section as seen on the line 5-5 of Fig. 4.

Referring more particularly to Figs. 1 and 2, 6 indicates a box-like metallic casing open at the upper end and provided with a register plate 7 which is intended to be flush with the floor when the furnace is installed. The casing 6 is provided with air inlets 8 which are disposed in such position that air will be drawn in from below the floor of the room. The casing 6 assists in making the structure fire-proof. Within the casing 6 is the furnace proper which consists of an apron 9 secured at its upper end to the register plate 7. Outside the periphery of the apron 9 are register openings 10 so that air may pass from the room downwardly between the apron 9 and the housing 6. Mounted within the apron 9 and spaced therefrom is an air housing or drum 11 closed at the upper end and secured to a cylindrical base 12. Cylindrical base 12 has an inclined bottom 13. Near the upper end of the drum 11 are air outlet ports 14. Ad-

jaacent the base 12 are air inlet ports 15. A ring 16 is disposed in the base 12 between the inclined bottom 13 and the side walls of the base, forming an annular chamber in the base to which a pipe 17 is connected.

A combustion chamber housing or drum 18 is secured to the bottom 13 of the base 12 and is open at the upper end. A ring 19 extends from the drum 11 to the upper end 65 of the drum 18, thereby forming with the drum 18, the drum 11, and the rings 16 and 19 an annular air heating chamber. Openings are formed in the ring 19 and openings registering therewith in the ring 16. Tubes 70 20 connect the openings in rings 19 and 16 thereby providing ducts for the passage of burnt gases from the upper end of the tubes to the chamber in the base 12 and out through the pipe 17. 75

A perforated plate 21 is secured across the bottom of the base member 12 and a burner 22 is mounted therein. The burner 22 is in the form of a cylindrical pipe with openings on the inner side shaped to produce flat 80 luminous flames. A feed pipe for the burner is indicated at 23, a pilot light tube for lighting the burner at 24, a lighting tube at 25', and a valve at 26'. As the latter are not features of my invention they are not described in detail. 85

Assuming that the burner 22 is lighted the flames are directed inwardly toward the center with their tips adjacent the center. Air for burning purposes is supplied in abundance through the perforated plate 21, there being an oversupply of air so that no carbon-monoxid is formed. Part of the air which passes in close to the base of the flame will pass outwardly through openings 25 formed at the base of drum 18 into the drum 11. This air is heated by direct contact with the flames and as the flames are spread in flat form a very efficient and effective heater is provided. The burnt gases pass up 100 through the center of the drum 18 to the upper portion of the drum 11 and downwardly through the tubes 20 to the chamber in the base 12, which is hereafter called a smoke box, and out through the pipe 17. 105 As the burnt gases move upwardly through the center of the drum 18 there is a tendency for the gas to expand at the center; a compression having been caused by reason of the flames being directed toward each other. 110 This assists in crowding the air out through openings 25. Some air is taken through

openings 8 in casing 6, passes downwardly between the apron 9 and the casing and under the lower part of the apron, into the chamber formed between the apron 9 and drum 11, some passing through the openings 15 and circulating about the tubes 20, and upwardly through the openings 14 and through the openings 26 in the register into the room. Other air enters from the room 10 through the openings 10 and takes the same path as the air which passes through the openings 8.

Referring particularly to Figs. 3, 4 and 5, a wall furnace is shown. This comprises an outer housing 31 to which a register plate 32 is secured. The latter plate is adapted to be installed flush with the wall of the room. Within the housing 31 and spaced therefrom is a housing 33 which is secured 20 to the register. A chamber 34 is formed between housings 31 and 33. Openings are provided in the register so that air may circulate about the housing 33. The chamber 34 provides insulation and makes the structure fire-proof. Within the housing 33 is a combustion chamber housing 35, forming an air heating chamber 36 between the housings 33 and 35, and a combustion chamber 37 between the housing 35 and the register plate 32. A flue passes through chamber 34 and connects chamber 36 with the outside of the housing 31 as indicated at 38.

A flue for burnt gases connects housing 35 and the outside air as indicated at 39. Heating ducts 40 pass through chamber 37, connecting the room with the air heating chamber 36 and providing means, whereby the hot burnt gases may circulate about the ducts and thereby heat the air passing from 40 the heated chamber into the room.

A baffle plate 41 directs the burnt gases forwardly producing a more efficient circulation of the hot gases. The housing 35 for the combustion chamber is open at the lower 45 end and is provided with an off-set 42 within which is disposed a burner 43 provided with tips for producing flat flames. Immediately above burner 43 are openings 44 in the wall of the housing 35. The operation 50 of the wall furnace is as follows: Air for combustion and for circulation in the room passes upwardly through flue 38, some of it passing into the chamber 36 and through heating ducts 40 into the room, thereby being heated indirectly. Part of the air passes 55 from flue 38 to feed the burner 43, the surplus passing close to the base of the burner jets through openings 44 into the chamber 36 and through heating ducts 40. Some of the air which is heated directly and also 60 heated indirectly instead of passing through heating ducts 40 will pass upwardly and above the housing 35 through the register into the room. The burnt gases passing upwardly 65 are directed along the heating ducts

by the baffle plate 41 and pass outwardly through flue 39.

It will be obvious that I have provided a furnace in which there is little wastage of heat and which is hygienic, fireproof, 70 and compact.

What I claim is:

1. A heating device, comprising a housing forming a combustion chamber having a relatively large air inlet, a fuel burner 75 mounted adjacent said air inlet, an air housing spaced from said combustion chamber housing and forming therewith an air heating chamber adapted to be connected to a room for indirect heating of air, means disposed adjacent the fuel burner placing the combustion chamber and air heating chamber in communication and providing for direct heating of air, and means for the exit of burnt gases communicating with said 80 combustion chamber and closed from said air heating chamber.

2. A heating device, comprising a housing forming a combustion chamber having a relatively large air inlet, a fuel burner mounted 90 in said combustion chamber adjacent said air inlet, an air housing spaced from said combustion chamber housing and forming therewith an air heating chamber adapted to be connected to a room for indirect heating of air, ports in the combustion chamber housing disposed adjacent the fuel burner and connecting the combustion chamber and air heating chamber and providing for direct heating of air, and means for the exit 95 of burnt gases communicating with said combustion chamber and closed from said air heating chamber.

3. A heating device, comprising a housing forming a combustion chamber having a 105 relatively large air inlet, a fuel burner mounted in said combustion chamber adjacent said air inlet, ports in said combustion chamber housing adjacent the fuel burner, a second housing surrounding said combustion chamber and forming therewith an air heating chamber for indirect heating of air, tubes for the burnt gases disposed in the air heating chamber and communicating with said combustion chamber, openings in the 110 second housing for the admission and outlet of air to the air heating chamber for indirect heating of air, and a flue for the exit of burnt gases communicating with said tubes.

4. A heating device, comprising a base 120 provided with an annular smoke box and a combustion chamber opening at the center, a burner in said combustion chamber, a combustion chamber housing mounted on said base and having air outlet openings adjacent the base, an air heating chamber housing mounted on the base and spaced from said combustion chamber housing and provided with openings adjacent the base and the top, tubes disposed in the chamber 125 130

formed between said combustion chamber housing and air heating chamber housing for the passage of burnt gases from the combustion chamber to the smoke box, and a flue 5 for the exit of burnt gases communicating with said tubes.

5. A heating device, comprising a base provided with an annular smoke box and combustion chamber opening at the center, 10 a burner in said combustion chamber, a cylindrical combustion chamber housing open at the upper and lower ends and mounted on said base and having air outlet openings in the walls thereof adjacent the base, a cylindrical air heating chamber housing mount- 15

ed on the base and spaced therefrom and closed at the upper end provided with openings adjacent the base and the top, a ring disposed at the top of the combustion chamber housing completing an annular air 20 heating chamber, tubes disposed between said ring and said smoke box in the air heating chamber for the passage of burnt gases, and a flue for the exit of burnt gases connected to said smoke box. 25

In witness that I claim the foregoing I have hereunto subscribed my name this 6th day of July, 1915.

RAYMOND H. VONDENBOSCH.
